PRESSURE REGULATING VALVE

Walter Czarnecki, Eddington, Pa., assignor to Eddington Metal Specialty Co., Eddington, Pa., a firm composed of Walter Czarnecki, Sr., Mary Czarnecki, Nellie Wojsowski, Wesley Czarnecki, Stanley Czarnecki, Walter V. Czarnecki, Jr., and Casimer Czarnecki.

Original application March 26, 1937, Serial No. 133,131. Divided and this application October 11, 1937, Serial No. 168,337.

5 Claims. (Cl. 137—153)

This invention relates to pressure regulating valves such as are commonly employed in connection with oil burners to insure that fuel under a proper pressure is delivered to the burner nozzle.

5 This application is a division of the copending application of Walter Czarnecki, Serial No. 133,131, filed March 26, 1937, and entitled "Fuel supply unit."

10 It is now common practice in this art to employ a pressure regulating valve that includes a port to the burner and a port which will bypass fluid back to the source of supply. A valve is associated with the port to the burner which ordinarily remains closed, but which is affected by pressure that is built up in the valve to open when a predetermined pressure is reached. The port to the bypass is also normally closed by a valve, but this valve is also opened when a predetermined pressure, usually greater than that at which oil is delivered to the burner, is attained by the fuel 20 in the valve.

15 The present invention is concerned with pressure regulating valves of this general type, and has as its foremost objective the provision of a novel and improved pressure regulating valve which is designed particularly with the thought of maintaining constant and uniform the pressure at which the fluid is delivered to the burner during long periods of service usage, and which 25 pressure regulating valve may also be adjusted with a degree of nicety heretofore unattained to vary the pressure at which fluid will be bypassed back to the source of supply.

20 Particular features and objects of the invention are associated with the provision of a novel type of valve assembly for controlling the bypassing of the fuel back to the source of supply. These and other more detailed objects and advantages will in part become apparent and in 30 part be hereinafter stated.

25 The invention, therefore, comprises a pressure regulating valve including a valve casing which is formed with a burner port and a bypass port, and novel valve assemblies associated and operable within the casing to control the burner and bypass ports.

30 For a full and more complete understanding of the invention reference may be had to the following description and accompanying drawing, wherein:

35 Figure 1 is a sectional view taken through a pressure regulating valve made in accordance with the precepts of this invention.

40 Figure 2 is an enlarged detailed view partly in section and partly in elevation of one modifica-

tion which may be carried out at the valve located at the burner port.

45 Figure 3 is an end elevational showing of the valve member controlling the flow of fuel through the bypass.

50 Figure 4 is a side elevational showing taken at right-angles to the showing of Figure 3, of the valve member of the latter.

55 Figure 5 is an end elevational showing similar to Figure 3 of a slightly modified form of valve member.

60 Figure 6 is a side view partly in section and partly in elevation of the valve member shown in Figure 5, and

65 Figure 7 is a detailed showing of the valve member per se which is brought out in Figure 2. In this view a certain part of the valve member is broken away and shown in section to clearly bring out the construction thereof.

70 Referring now to the drawing, wherein like reference characters denote corresponding parts, the pressure regulating valve shown in Figure 1 is shown as comprising a main body portion in the form of a casing C, which casing is of a hollow construction so as to house the various valve parts. At one end the casing C is provided with a threaded opening designated 10, and at the opposite end with another threaded opening 11.

75 A passageway 12 is formed in a side wall of the casing C, and constitutes means for establishing communication between the interior of the casing C and a suitable source of fuel supply, which may be a fuel supply unit such as shown in the copending application above identified, an oil pump, or any other means for supplying fluid fuel under pressure.

80 The casing C is formed with a flange 13 that surrounds the passageway 12, and this flange is provided with a plurality of bolt holes 14 which are designed to accommodate headed bolts in securing the pressure regulating valve as an entirety in position, as is clearly brought out in the copending application above identified.

85 Screwed into the threaded opening 10 is a plug member 15 which is formed with a threaded socket 16; this socket 16 being designed to have connected thereto a suitable conduit which leads to an oil burner. The plug member 15 is also formed with an extension 17 which projects into the hollow casing C, and this plug extension 17 is 90 provided with a cylindrical socket 18 which slidably receives a valve member 19.

95 A passageway 20 connects the sockets 16 and 18, and establishes communication therebetween. Speaking with respect to the axis of the socket 25

18, the wall of the plug extension 17 is provided with a plurality of radially extending openings 21 which may be of any desired number, such as four in the illustrated embodiment.

5 The valve member 19 is formed with a conical tip 22 which when fitted in the extremity of the passageway 20 serves to seal the same, and cut off communication to the oil burner. However, when the valve member 19 has slid in the socket 18, to unseat the conical tip 22 from the extremity of the passage 20, communication from the interior of the casing C through the passageways 21 to the passage 20 and socket 16 is established.

15 A piston element designated 23 is shown as 18 slidable in a cylindrical portion of the casing C, which cylindrical portion is designated 24. In order to establish a properly effective seal between the piston 23 and the cylindrical part 24 of the casing C a packing element is shown at 25 20 as being held in position by a ring 26 which may be placed around a reduced cylindrical part 27 of the piston 23.

25 Extending upwardly from the reduced portion 27 of the piston 23 is a spherical-like projection 28 formed with a socket 29 which receives a complementally spherically shaped member 30 formed on the valve member 19.

30 A coil spring designated 31 engages the piston 23 at one end, and at the other end is received 35 in a seat 32 which is formed in an end closure 33 that is screwed into the threaded opening 11. It is evident that the spring 31 normally urges the piston 23 upwardly (speaking with reference 40 to the showing of Figure 1) and thus maintains the conical tip 22 of the valve member 19 seated in the valve seat defined by the end of the passage 20. However, when sufficient pressure has been built up in the fluid within the casing C above the piston 23 the latter will be moved downwardly against the influence of the spring 31 to 45 unseat the conical tip 22 of the valve member 19 from the end of the passage 20.

45 Just beneath the spherical projection 28 the reduced portion 27 of the piston 23 is provided 50 with a plurality of radially disposed passageways 34, which may be of any desired number, as the four illustrated in the drawing. These passageways 34 intercept centrally of the piston, and communicating therewith is a central passage 35 that extends axially of the piston 23. This passageway 35 opens into a cup-like depression 36 which is formed in the piston 23.

55 A housing member 37 has one end received in the cup-like depression 36, and this end of the housing 37 is formed with an end structure referred to in its entirety as 38. This end structure 38 includes a recess 39 into which opens the passage 35. Extending from the recess 39 into the interior of the housing 37 are a plurality of 60 longitudinally extending passages 40. The central part of the end structure 38 is formed with the recess 41, the edge of which constitutes a valve seat in a manner to be hereinafter described.

65 At this point it is well to note that the housing 37 is provided with a plurality of openings 42 in the walls thereof, and which openings 42 establish communication between the interior of the housing 37 and the interior of the casing C thereabout.

70 A valve member 43 is slidably positioned in the housing 37, and at its upper end is formed with a truncated conical projection 44. This conical projection 44 is provided with a cross cut or kerf designated 45. This cross cut or kerf 45 opens on 75 each side of the conical projection 44. The valve

member 43 is provided with a central passageway 46 that communicates with the crosscut 45. A coil spring 47 has one end fitted about a projection 48 formed on the valve member 43, and the other end of the spring 47 is fitted about a projection 49 that is formed on a backing member 50. This backing member 50 bears against a threaded stem 51 that is screwed into a plug member 52 which is threaded into the end of the housing 37 that is threaded as shown at 53. It is evident that the threaded stem 51 may be rotated to adjust the tension afforded by the spring 47.

When the valve member 43 is urged upwardly by the spring 47 so that the truncated conical extension 44 engages the edge of the valve seat 41, the cross cut 45 will be almost, but not quite, entirely closed, providing just sufficient opening therethrough to allow a so-called bleeding action, which is desirable in pressure valves of this type. This bleeding action of the fluid is through the 20 openings 42 to the bypass port shown at 54. The bypass port 54 communicates with a threaded socket 55 which may have connected thereto a suitable conduit constituting the bypass back to the source of fuel supply.

25 However, when sufficient pressure is built up on the fluid passing through the passages 34, 35, 39 and 40 the valve member 43 will be affected by the built up pressure to be moved against the influence of the spring 47 to open up communication between the passages 40 and 46, and thereby provide an adequate bypassing of fluid through the bypass port 54.

30 It is notable that the housing 37 moves with the piston 23, and this housing 37 is formed with a shoulder at 56 which serves to limit movement of the piston 23. Obviously when the shoulder 56 engages the edge of the bore 57 which is formed in the end closure 33, further movement of the piston 23 in a downward direction is inhibited.

35 The bore 57 in the end closure 33 is enlarged and threaded as shown at 58, and screwed thereinto is a cap member 59 having a cup-like recess 60 which accommodates the threaded stem 51.

40 Referring now more particularly to Figures 5 and 6, a modified form of sliding valve is shown, and which is intended to replace the valve member 43 of Figures 3 and 4. In this modification the valve member 43 is replaced by a cup-like valve member 61 having a recess 62 which receives one end of the spring 47; the longer passage 46 being replaced by the central passage 63.

45 When the pressure regulating valve illustrated in Figure 1 is installed in a position which is inverted from that shown there may be a tendency for sediment to collect in the passages 21. In order to avoid any possibility of such sediment collection interfering with the proper operation of the valve 19 at the burner port a somewhat modified form of valve may be used at this point; such modification being brought out in Figures 2 and 7. In this form the plug extension 17 is not formed with the radial passages 21, but the socket 18 receives a valve member 64, the cylindrical walls of which are provided with a plurality of cuts or kerfs 65. These cuts 65 establish communication between the interior of the casing C and the passage 20 when the valve member 64 is unseated from the valve seat defined by the passage 20.

50 While preferred specific embodiments of the invention are hereinbefore set forth it is to be clearly understood that I am not to be limited to the exact constructions illustrated and described, because various modifications of these 75

details may be provided in putting the invention into practice within the purview of the appended claims.

I claim:

5 1. In a fuel supply unit of the character described, a pressure regulating valve comprising a hollow casing formed with inlet, burner and bypass ports, a passageway communicating with the burner port and having an edge constituting 10 a valve seat, a valve member adapted to be seated in said valve seat, a piston slidable in the casing and carrying said valve member, a spring normally urging said valve member into position in which the valve is seated in the valve seat, a 15 housing movable with the piston, a valve member movable in said housing, the piston, housing and valve member being formed with openings which establish communication between the interior of the casing and bypass port when the 20 valve member of the housing is in an open position, said housing and valve member movable therein being provided with means to establish a bleeding to the bypass port through the said openings when the valve member in the housing 25 is in a closed position, and a spring in the housing normally maintaining said valve member in the housing in a closed position, said valve member in the housing being movable against the influence of the spring under the influence of 30 pressure of fluid in the casing.

30 2. In a fuel supply unit, a pressure regulating valve comprising a casing formed with inlet, burner and bypass ports, a piston slidable in the casing and having a reduced portion centrally 35 thereof, packing means carried by the reduced portion for sealing the piston with the casing, a valve member carried by the reduced portion of the piston which valve member cooperates with the burner port to establish or cut off communication therethrough, the reduced portion of the piston being formed with a radially extending passage, the piston also being formed with an axially extending passage communicating with the radially extending passage, the 40 piston also being formed with a cup-like recess into which opens the axially extending passage, a housing received in the cup-like recess and having an end structure formed with a recess in communication with the axially extending passage of the piston, the end structure also being formed with an opening establishing communication to the bypass port, the end structure of the housing being formed with a valve seat, a valve member movable in the housing formed with a conical tip adapted to be seated in said valve seat, said tip being formed with a cross cut, the valve member having a passage extending therethrough in communication with the cross cut, a spring in the casing normally urging the piston to affect the last mentioned valve member to cut off communication to the burner, and a spring in the housing normally urging the valve member in the housing to seat a conical tip in the valve seat in the end structure of the housing, and means for varying the tension of said last mentioned spring.

45 3. A pressure regulating valve comprising a casing formed with an inlet, a burner, and a bypass port, said casing being formed with a bore, a piston slidable in said bore and carrying a valve which cooperates with the burner port controlling the flow of fluid therethrough, a closure at the end of the casing opposite from the burner port, said closure being formed with a shoulder, a sleeve carried by the piston and movable therewith, said sleeve having a shoulder adapted to engage the shoulder on the closure to limit movement of the piston, a spring disposed about said sleeve, engaging the piston at one end, and the shoulder of the closure at the other to normally urge the valve that is carried by the piston into closed position with respect to the burner port, said piston having a passageway extending through the head thereof, communicating with the interior of said sleeve, and a valve mechanism disposed interiorly of the sleeve for controlling the passage of the fluid therethrough, said sleeve being formed with openings that communicate with the bypass port.

50 4. A pressure regulating valve comprising a casing formed with an inlet, a burner, and a bypass port, said casing being formed with a bore, a piston slidable in said bore and carrying a valve which cooperates with the burner port controlling the flow of fluid therethrough, a closure at the end of the casing opposite from the burner port, said closure being formed with a shoulder, a sleeve carried by the piston and movable therewith, said sleeve having a shoulder adapted to engage the shoulder on the closure to limit movement of the piston, a spring disposed about said sleeve engaging the piston at one end, and the shoulder of the closure at the other to normally urge the valve that is carried by the piston into closed position with respect to the burner port, said sleeve being formed with openings communicating with the bypass port and having a head which engages with the piston, and which head is formed with passageways com-

5 10 15 20 25 30 35 40 45 50 55 60 65 70 75

the piston which valve member cooperates with the burner port to establish or cut off communication therethrough, the reduced portion of the piston being formed with a radially extending passage, the piston also being formed with an axially extending passage communicating with the radially extending passage, the piston also being formed with a cup-like recess into which opens the axially extending passage, a housing received in the cup-like recess and having an end structure formed with a recess in communication with the axially extending passage of the piston, the end structure also being formed with an opening establishing communication between said recess and the interior of the housing, the cylindrical walls of the housing being formed with an opening establishing communication to the bypass port, the end structure of the housing being formed with a valve seat, a valve member movable in the housing formed with a conical tip adapted to be seated in said valve seat, said tip being formed with a cross cut, the valve member having a passage extending therethrough in communication with the cross cut, a spring in the casing normally urging the piston to affect the last mentioned valve member to cut off communication to the burner, and a spring in the housing normally urging the valve member in the housing to seat a conical tip in the valve seat in the end structure of the housing, and means for varying the tension of said last mentioned spring.

5 10 15 20 25 30 35 40 45 50 55 60 65 70 75

4. A pressure regulating valve comprising a casing formed with an inlet, a burner, and a bypass port, said casing being formed with a bore, a piston slidable in said bore and carrying a valve which cooperates with the burner port controlling the flow of fluid therethrough, a closure at the end of the casing opposite from the burner port, said closure being formed with a shoulder, a sleeve carried by the piston and movable therewith, said sleeve having a shoulder adapted to engage the shoulder on the closure to limit movement of the piston, a spring disposed about said sleeve, engaging the piston at one end, and the shoulder of the closure at the other to normally urge the valve that is carried by the piston into closed position with respect to the burner port, said piston having a passageway extending through the head thereof, communicating with the interior of said sleeve, and a valve mechanism disposed interiorly of the sleeve for controlling the passage of the fluid therethrough, said sleeve being formed with openings that communicate with the bypass port.

5. A pressure regulating valve comprising a casing formed with an inlet, a burner, and a bypass port, said casing being formed with a bore, a piston slidable in said bore and carrying a valve which cooperates with the burner port controlling the flow of fluid therethrough, a closure at the end of the casing opposite from the burner port, said closure being formed with a shoulder, a sleeve carried by the piston and movable therewith, said sleeve having a shoulder adapted to engage the shoulder on the closure to limit movement of the piston, a spring disposed about said sleeve engaging the piston at one end, and the shoulder of the closure at the other to normally urge the valve that is carried by the piston into closed position with respect to the burner port, said sleeve being formed with openings communicating with the bypass port and having a head which engages with the piston, and which head is formed with passageways com-

municating with the interior thereof, the head of the piston being formed with a passageway that extends therethrough and establishes communication from the inlet opening to the passageways in the head of the sleeve, a valve member slideable in said sleeve, a spring normally urging said

valve member in closed position, said valve member being provided with a cut to establish a bleed, and means for adjusting the tension of said last mentioned spring.

WALTER CZARNECKI. 5
